(57) **CLAIM**

The ornamental design for a toothbrush, as shown and described.

DESCRIPTION

FIG. 1 is a perspective view of the toothbrush embodying the new design;

FIG. 2 is a right side view of the toothbrush, the left side view being a mirror image thereof;

FIG. 3 is a front view thereof;

FIG. 4 is a rear view thereof;

FIG. 5 is an enlarged top view thereof; and,

FIG. 6 is an enlarged bottom view thereof.

FIGS. 1–6 show portions of the toothbrush in phantom lines. The portions shown in phantom lines form no part of the claimed design.
